FIG. 1 is a top, front and right side perspective view of a solar table light showing my new design;

FIG. 2 is a front elevational view thereof;

FIG. 3 is a left side elevational view thereof;

FIG. 4 is a bottom plan view thereof;

FIG. 5 is a top plan view thereof;

FIG. 6 is a rear elevational view thereof; and,

FIG. 7 is a right side elevational view thereof.

The broken-line disclosure of elements in the views are understood to be functional aspects of the article in which the design is embodied and form no part of the claimed design.
